UNITED STATES PATENT OFFICE.

RALPH C. SEYMOUR, OF LARCHMONT, NEW YORK, ASSIGNOR TO SCHWARTZ, SEYMOUR & COMPANY, INC., A CORPORATION OF NEW YORK.

PRINTING PRESS.

Original application filed August 24, 1920, Serial No. 405,638. Divided and this application filed May 16, 1921. Serial No. 469,845.

To all whom it may concern:

Be it known that I, RALPH C. SEYMOUR, a citizen of the United States, residing at Larchmont, in the county of Westchester and State of New York, have made certain new and useful Improvements in Printing Presses, of which the following is a specification:

The invention relates to novel mechanism in a printing press for raising a roll of paper from the floor and placing it in feeding position on the press.

This application is a division of my co-pending application Ser. No. 405,638 filed August 24, 1920, patented March 13, 1923, No. 1,448,006.

Objects and advantages of the invention will be set forth in part hereafter and in part will be obvious herefrom; or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention:

Of the drawings:

Fig. 1 is a side elevation of a part of a printing press embodying the invention, and corresponds to Fig. 7 and the left hand part of Fig. 1 of my said application Ser. No. 405,638, patented March 13, 1923, No. 1,448,006:

Fig. 2 corresponds to the left hand part of Fig. 1, but shows the mechanism and paper rolls in a different position;

Fig. 3 is a vertical, transverse section on line 3—3 of Fig. 2;

Figs. 4 and 5 correspond to Fig. 2, but show, respectively, the mechanism and paper rolls in different positions; and

Fig. 6 is an enlarged, horizontal section on line 6—6 of Fig. 5.

In the parent application Ser. No. 50 405,638, the invention is shown applied both to an offset roll handling mechanism and to a printing paper roll handling mechanism, certain features of the invention being applicable to both of these mechanisms, while 55 certain other features of the invention are especially applicable to one of the aforementioned mechanisms or to the other. The present application is directed more especially to those features of the invention 60 which are applicable either generally to both said mechanisms or especially to the printing paper roll handling mechanism.

By the present invention a single workman can relatively easily and quickly supply a new roll of printing paper to the press, and the new web can be attached to the old with little or no delay in the running of the press. The paper roll handling mechanism is capacitated to engage the paper roll 70 while resting upon the floor or other suitable support, engaging with the ends of the mandrel in the center of the roll, raising it to the trackways on the frame, and delivering it to the trackways without any lifting 75 or handling of the roll. The lifting mechanism is constructed so that a single workman at a single place or station can lift the paper roll to the required position, the mechanism also holding the roll at any desired intermediate point or position.

Other features and advantages of the invention will be set forth in connection with the detailed description, while other features will be apparent without explanation; it being understood that both the preceding and following descriptions are illustrative and explanatory of the invention and not restrictive thereof.

Referring now in detail to the accompanying drawings, illustrating by way of example the present preferred embodiment of the invention, Fig. 1 of the present drawings shows parts of the printing press which are

illustrated in Fig. 7 and in the left hand part of Fig. 1 of the parent application Ser. No. 405,638, already referred to. One of the plate cylinders of the printing press 5 is indicated by 1, having its shaft 2 journaled in the press frame. The inking mechanism of the plate cylinder is indicated diagrammatically at 3. The impression cylinder 4 cooperates with the plate cylinder 1 10 to make the first impression, the web α running between the cylinders.

Referring now more particularly to the mechanism for handling the roll of printing paper which is to be supplied to the press, 15 a pair of bearings 10 are formed, respectively, in a pair of trackways 11, which are formed on the upper side or edge of a part of the press frame. The trackways 11 are approximately horizontal, but preferably are 20 very slightly inclined inwardly or toward the printing mechanism proper so as to facilitate the rolling or sliding of the new roll of printing paper into position in the bearings 10. A second pair of bearings 12 25 for the mandrel of the roll α of printing paper are preferably provided, similarly to the two pairs of bearings 29 and 31 shown in Fig. 1 of the parent case for the offset roll.

30 In the illustrated embodiment, a pair of guideways 13 and 14 are provided on the ends of the press frame, and these are preferably vertically or approximately vertically arranged. These guideways are preferably T shaped, as best shown in Fig. 6. Mounted to slide or travel along the guideways, respectively, are saddles 15 and 16, which engage beneath the ends of the mandrel 17. The saddles are formed with a 35 guide member 20, which is provided with a face 21 engaging with the face of the guideway 13, and is also provided with side portions 22 and 23 extending along the sides of the guide 13, and with inner end portions 40 24 and 25 which extend back of the guide 13. Thus the saddles embrace their respective guides, but are slidable therealong.

Each of the saddles is provided with a 45 roll-supporting member, consisting of a part 26 extending outwardly from the body 20 of the saddle, the upper surface of the member 26 engaging beneath the corresponding end of the mandrel 17. This upper surface of the member 26 is preferably inclined inwardly and downwardly toward the corresponding guideway 13 or 14, so that as the roll is lifted the action of gravity will cause the mandrel 17 to rest both on the 55 saddles against the faces of the guides 13 and 14, and thus be secure from rolling off the supports. This construction enables the mandrel 17 to pass over the saddles 20 when they are depressed but very little below the 60 mandrel, and obviates the necessity of any special fastenings or other mechanism for

holding the mandrel in place to guard against its slipping off the saddles after the roll α has been lifted from the floor or other support. This construction also permits and facilitates the sliding or rolling of the 70 mandrel from the saddles onto the trackways 11 when the saddles had been raised to the level of the trackways.

Means are provided for raising and lowering the saddles and for holding them in any 75 desired position along their path of travel. As embodied, two bars 30 and 31 extend downwardly, respectively, from the saddles 15 and 16, and may conveniently extend into depressions in the floor. On its inner edge 80 the bar 30 is provided with a straight gear 32, and bar 31 is provided with a like gear 33. Meshing with the gear 32 is a gear wheel 36, and meshing with the gear 33 is a gear wheel 37, both gear wheels being fixed 85 on a shaft 38, which shaft is journaled at 39 and 40 in the machine frame.

The embodied form of means for rotating the shaft 38 comprises a ratchet wheel 44 fixed on the shaft 38, a lever 45 loosely 90 pivoted on the shaft, and a pawl 46, which is pivoted on lever 45 and engages with the teeth of the ratchet 44.

Suitable detent means are provided for the ratchet wheel 44, and preferably in connection therewith a release and a braking mechanism, whereby the saddles may be lowered under control either with or without a load. In the parent case this mechanism is shown applied to the same construction 100 of pawl and ratchet mechanism for the offset roll, and in the same relation. As embodied, in Fig. 5, a detent 47 is pivoted at 48 on the machine frame, and is provided with a tail 49 which may be actuated by 105 the foot of the workman. Extending from the tail 49 is an arm 50, provided with a brake shoe 51 adapted to engage with a brake pulley or roll 52, fixed on shaft 38. A spring 53 yieldably holds the detent to 110 the ratchet and the brake off from the brake pulley.

The manner of operation of the mechanism will be clear in the main from the foregoing. In Fig. 2 of the drawings, the 115 web from paper roll α is shown running into the press and a new roll of paper α' is shown resting upon the floor, and with the saddles 26 in position therebeneath, ready to lift the roll by its mandrel 17. In Fig. 4, the now almost depleted roll α has been moved from the bearings 10 to the bearings 12 to make room for the new roll α' , and the roll α' has been raised, through the actuation of hand lever 45, and the upper surface of the saddles 26 are shown just flush with the corresponding trackways 11, whereby the mandrel 17 of the roll α' will be rolled or slid with very little effort onto and along the trackways 11. 125 130

The inclination of the trackways may be sufficient so that the roll will itself, under the action of gravity, move slowly along the trackway until it rests in the bearings

5 10. In Fig. 5 the lead end of the web α' is shown attached to the tail end of the exhausted web α , the new web being thereby led through the press by the old web in a well known manner.

10 15. By stepping on lever or tail 49, the detent 47 is lifted out of pawl 48, and brake 51 is applied and the saddles are slid down to roll-receiving position, and if desired the roll itself may be lowered under control.

The invention in its broader aspects is not limited to the details of construction shown and described in the present exemplary embodiment, but changes may be 20 made therein within the scope of the accompanying claims without departing from the principles of the invention and without sacrificing its chief advantages.

What I claim is:

25 1. In combination in a printing press, bearings in fixed position on the press side frames rotatively supporting the mandrel of a paper roll, and means for elevating a paper roll and delivering it to said bearings 30 including traveling saddles extending rearwardly from the ends of the press frame and slidably associated therewith and adapted to engage beneath the ends of the mandrel of a paper roll resting on the floor 35 and to lift the roll.

2. In combination in a printing press, trackways on the press side frames and bearings for rotatively supporting the ends of a paper roll mandrel, upwardly extending guideways terminating at the trackways and saddles movable along the guideways and extending from the guideways in the opposite direction from the trackways.

3. In combination in a printing press, trackways on the press side frames and bearings for rotatively supporting the ends of a paper roll mandrel, upwardly extending guideways terminating at the trackways and saddles movable along the guideways and extending from the guideways in the opposite direction from the trackways, the guideways also extending downwardly to permit the ends of the mandrel of a paper roll resting on the floor to pass above said saddles.

4. In combination in a printing press, bearings for the ends of the mandrel of a paper roll, a pair of upwardly extending guideways terminating substantially at the level of the bearings, and a pair of saddles movable on the guideways and having supporting means for the ends of the mandrel on the opposite sides of the guides from the bearings, and adapted to direct said mandrel ends against said guideways.

5. In combination in a printing press, a pair of trackways formed on the tops of extensions of the side frames of the press, two sets of bearings formed in the trackway, each set adapted to rotatably support the ends of a paper roll mandrel, upwardly extending guideways on the ends of said extensions, and terminating at the trackways, and a pair of mandrel supporting saddles movable along, and extending outwardly from the guideways, and means for moving the saddles together.

6. In combination in a printing press, a pair of trackways formed on the tops of extensions of the side frames of the press, and inclined slightly downwardly toward the press, two sets of bearings formed in the trackway, each set adapted to rotatably support the ends of a paper roll mandrel, upwardly extending guideways on the ends of said extensions, and terminating at the trackways, and a pair of mandrel supporting saddles movable along, and extending outwardly from the guideways, and means for moving the saddles together.

7. In combination in a printing press, a pair of trackways formed on the tops of extensions of the side frames of the press, two sets of bearings formed in the trackway, each set adapted to rotatably support the ends of a paper roll mandrel, upwardly extending guideways on the ends of said extensions, and terminating at the trackways, and a pair of mandrel supporting saddles movable along, and extending outwardly from the guideways, and means for moving the saddles together, the guideways extending downwardly to permit the mandrel of a paper roll on the floor to pass above the saddles.

8. In combination in a printing press, a substantially horizontally disposed trackway, a pair of saddles with tops sloping toward the press, vertical guideways on the press on which the saddles move up and down, and means for simultaneously operating the saddles, whereby the mandrel of a roll of paper is lifted to the level of the trackway and rolls down the sloping tops of the saddles onto the trackway.

9. In combination in a printing press, a trackway, substantially horizontally disposed, but with a slight slope toward the press, a pair of bearings for a paper roll mandrel at the lower end of said trackway, a pair of saddles the tops of which slope toward the press, guideways on the press with which the saddles slidably engage, and means for simultaneously operating the saddles whereby a roll of paper is lifted to the trackway and rolls off the saddles and along the trackway to the said bearings.

10. In combination in a printing press a pair of trackways for the ends of a paper roll mandrel, a pair of guideways extend-

- ing upwardly to the trackways, a pair of roll lifting devices moving along the guideways, and common actuating means connected to both lifting devices and extending across the press below the trackways.
11. In combination in a printing press a pair of trackways for the ends of a paper roll mandrel, a pair of guideways extending upwardly to the trackways, a pair of roll lifting devices moving along the guideways, and common actuating means connected to both lifting devices and extending across the press below the trackways, the guideways extending downwardly so that the mandrel of a paper roll resting on the floor may pass above the lifting devices.
12. In combination in a printing press a pair of trackways for the ends of a paper roll mandrel, a pair of guideways extending upwardly to the trackways, a pair of roll lifting devices moving along the guideways, and including gear-toothed members, and common actuating means having gear-toothed members meshing with the first-mentioned gear-toothed members connected to both lifting devices and extending across the press below the trackways.
13. In combination in a printing press a pair of trackways for the ends of a paper roll mandrel, a pair of guideways extending to, and terminating upwardly at, the trackways, a pair of roll lifting devices, extending from the guideways in the opposite direction from the trackways, moving along the guideways, and including gear-toothed members, and common actuating means for said roll lifting devices having gear-toothed members meshing with the first-mentioned gear-toothed members, connected to both lifting devices and extending across the press below the trackways, the guideways extending downwardly so that the mandrel of a paper roll resting on the floor may pass above the lifting devices.
14. In combination in a printing press a pair of bearings for rotatively supporting the ends of a paper roll mandrel, means for conveying a paper roll thereto including guideways, a pair of mandrel-engaging lifting saddles traveling on the guideways, gear racks extending from the saddles, gear pinions meshing with the racks, a shaft on which the pinions are fixed and extending across the press, and means whereby the shaft may be rotated.
15. In combination in a printing press a pair of bearings for rotatively supporting the ends of a paper roll mandrel, means for conveying a paper roll thereto including guideways, a pair of mandrel-engaging lifting saddles traveling on the guideways, gear racks extending from the saddles, gear pinions meshing with the racks, a shaft on which the pinions are fixed and extending across the press, and means whereby the shaft may be rotated.
16. In combination in a printing press a pair of bearings for rotatively supporting the ends of a paper roll mandrel, means for conveying a paper roll thereto including guideways terminating at substantially the level of said bearings, a pair of mandrel-engaging lifting saddles traveling on the guideways, gear racks extending from the saddles, gear pinions meshing with the racks, a shaft on which the pinions are fixed and extending across the press, the shaft and pinion being below the level of the bearings, and means whereby the shaft may be rotated.
17. In combination in a printing press a pair of bearings for rotatively supporting the ends of a paper roll mandrel, means for conveying a paper roll thereto including guideways, a pair of mandrel-engaging lifting saddles traveling on the guideways, and extending from the guideways on the opposite side from the bearings, gear racks extending from the saddles, gear pinions meshing with the racks, a shaft on which the pinions are fixed and extending across the press, and means whereby the shaft may be rotated.
18. In combination in a printing press a pair of bearings for rotatively supporting the ends of a paper roll mandrel, means for conveying a paper roll thereto including guideways terminating at substantially the level of said bearings, a pair of mandrel-engaging lifting saddles traveling on the guideways, and extending from the guideways on the opposite side from the bearings, gear racks extending from the saddles, gear pinions meshing with the racks, a shaft on which the pinions are fixed and extending across the press, the shaft and pinions being below the level of the bearings, and means whereby the shaft may be rotated.
19. In combination in a printing press a substantially horizontally disposed trackway, upwardly extending guideways carried on the end of the press frame and cooperating therewith, saddles slideable on the guideways, and means located entirely below the level of the trackway for raising the saddles simultaneously for lifting a paper roll onto the trackway.
20. In combination in a printing press a substantially horizontal trackway, substantially vertical guideways cooperating therewith, saddles slideable on the guideways, a horizontally extending shaft, means operatively connecting the shaft and saddles whereby the saddles are simultaneously raised upon rotation of the shaft, and manually operated means for rotating the shaft.
21. In combination with a printing press,

vertical guides on the ends of the side frame of the press, saddles slideable on said guides, a horizontally extending shaft adjacent the saddles, means operatively connecting the shaft and the saddles, and means for rotating the shaft.

22. In combination with a printing press, vertical guides on the ends of the side frame

of the press, saddles slideable on said guides, a horizontally extending shaft adjacent the ¹⁰ saddles, pinions carried by the shaft, racks carried by the saddles, meshing with the pinions, and means for rotating the shaft.

In testimony whereof, I have signed my name to this specification.

RALPH C. SEYMOUR.
